FIG. 3.

UNITED STATES PATENT OFFICE.

WINTHROP K. HOWE, OF ROCHESTER, NEW YORK, ASSIGNOR TO GENERAL RAILWAY SIGNAL COMPANY, OF GATES, NEW YORK, A CORPORATION OF NEW YORK.

AUTOMATIC TRAIN-CONTROL SYSTEM.

1,411,571.

Specification of Letters Patent.

Patented Apr. 4, 1922.

Application filed July 10, 1915. Serial No. 39,181.

To all whom it may concern:

Be it known that I, WINTHROP K. HOWE, a citizen of the United States, and a resident of the city of Rochester, in the county of 5 Monroe and State of New York, have invented a new and useful Automatic Train-Control System, of which the following is a specification.

This invention relates to improvements in 10 systems for automatically controlling railway vehicles, and more particularly to such systems in which the movements of the vehicles are controlled, in some appropriate way, by the energization or deenergization of suitable control relays on said vehicles, said energization or deenergization being controlled by devices arranged along the trackway over which the vehicles pass.

One of the principal objects of the invention 20 is to construct and arrange the parts of a train control system of the character described so that the operation of the system will not be affected if more than one unit equipped with the train control apparatus is included in the train, as for instance, if the train includes two or more locomotives or motor cars, each locomotive or motor car being equipped with the train control apparatus.

30 A further object of the invention is to devise a simple and reliable train control apparatus, circuits and electrical connections therefor which will properly control the energization of the control relay on each locomotive or motor car included in a train, regardless of the number of locomotives or motor cars, and regardless of the length of the train or the length of the sections or blocks into which the track is divided.

40 Other objects and advantages will appear as the description of the invention progresses, and the novel features of the invention will be particularly pointed out in the appended claims.

45 Generally stated, the invention consists in providing a comparatively short control section for each block section which control section is arranged to maintain the control device at the entrance to that block 50 section in the condition required by the condition of traffic in the block sections ahead until the entire length of the train has passed that control device.

The invention further consists in the parts, 55 and in the arrangements and combinations of parts, more fully set forth hereinafter.

In describing the invention in detail, reference is had to the accompanying drawing, wherein I have illustrated a preferred physical embodiment of my invention, and 60 wherein like characters of reference designate corresponding parts throughout the several views, and in which:

Figure 1 is a diagrammatic illustration of a railway train and a track for said train, 65 and shows the arrangement of the circuits and the parts, associated with the train and with the track, which embody the invention and which are suitable to control properly the movement of the train, said figure showing the parts in their normal positions and in the condition existing when a train approaches one of the ramps or control devices along the trackway; Fig. 2 is a diagrammatic illustration similar to Fig. 1 70 and shows the position of the parts of the train control system after part of the train has passed one of the control devices along the trackway, said positions of the parts corresponding to the condition where the 75 train may safely proceed unrestrained by the control system; Fig. 3 is a diagrammatic illustration similar to Fig. 1 and showing a slightly modified arrangement of the circuits.

85 Referring to the accompanying drawings, one track rail 1 of the railway track is electrically continuous, the separate rails thereof being bonded together in any manner; and the other track rail 2 of said railway 90 track is divided into electrically distinct sections A, B, C, D and E, in any suitable way, as by insulating joints 3. The sections A, 95 C and E are of any appropriate length to obtain the desired spacing of the train, and will be hereinafter termed block sections. The sections B and D are comparatively short and may be as short as convenient, providing they are longer than the greatest distance between any two successive pairs 100 of wheels, that is, each of these sections B and D is long enough so that there will be always some wheels of the train on it as the train passes.

105 For convenience in description these sections B and D will be hereinafter termed control sections. While only two control sections B and D and an intermediate block section C are shown in the drawing, it is to be understood that the same arrangement 110 is carried out throughout any desired length of the track, a control section being located

at the entrance to each block section as shown in the drawing, the direction of normal traffic being indicated by an arrow X. Across the two track rails 1 and 2 at one end of each block section is connected a suitable source of electric current, such as a battery 4, and also connected across the track rails 1 and 2 at the other end of each block section by conductors 5 and 6 is a track relay 7. There are two controlling circuits shown in the drawings for the control sections B and D which are the same; and the parts and conductors of the control section D have the same reference characters as the corresponding parts and conductors of the control section B, with an exponent "1" added thereto. These track relays 7 together with the track rails 1 and 2 and the batteries 4 constitute the well known normally closed track circuit, as will be understood by those skilled in the art of railway signalling. The track relays 7 are normally energized and their armatures will be normally held in their upper position, as shown in Fig. 1. Adjacent to each short control section is a contact rail or ramp 11, which is supported on the ties of the track but insulated therefrom in any suitable way. Associated with each ramp is a ramp relay 12, and a suitable source of electric current as a battery 15, which is arranged to be connected to the track rail 1 and to the corresponding ramp 11.

The wires or electrical connections between the different operative parts hereinbefore described will not be described in detail since these connections and the different operating circuits established will be fully set forth hereinafter in the description 40 of the operation.

The apparatus on the vehicle for controlling the movement thereof in accordance with the conditions along the trackway, which are evidenced by the condition of the 45 ramps located along the track, may be of any suitable construction, but is illustrated as constructed and arranged so that it will not be affected if a difference of potential exists between a ramp and a track rail, but will be set into operation in case no such 50 difference of potential exists. The railway train is shown diagrammatically as comprising two pairs of wheels 16 and 18 and their connecting axles 17 and 19 respectively 55 which represent the wheels of separate cars or locomotives and which are connected by a bar 20 representing the frames of the cars or locomotives. A bracket or supporting arm 21 of wood or other insulating material 60 is suitably fixed to the axle, journal box or frame of each vehicle, provided with the train control apparatus, and is shown in the drawings as supported on the axle of the rear pair of wheels 18; and movably supported on this bracket 21 is a shoe 22 which

is pressed downwardly by a spring 23. This shoe 22, when raised, serves to open a normally closed circuit and to accomplish this purpose, said shoe may have a button 24 of insulating material at its upper end which bears against the underside of a contact spring 25 cooperating with contact member 26, so that when said shoe is raised, the contact spring 25 is separated from the contact member 26. The contact spring 25 and the contact member 26 are suitably secured to the bracket 21, which, being of insulating material, serves to insulate said contact spring and said contact member from each other and from the frame of the vehicle. On the vehicle is a control relay 27 having two armatures 28 and 29. One armature 28 of the control relay 27 controls a local circuit for normally retaining said relay energized from a local source of current, as a battery 30 carried by said vehicle, when the contact spring 25 is pressed against the contact member 26; and the other armature 29 of said relay controls a local circuit for a device K by means of which the movement 85 of the vehicle is controlled. This device K may be of any suitable construction which is set into operation when deenergized, and since this device K forms no part of the present invention and various devices well known in the art will satisfy its requirements, a detail description of said device K will not be given here.

Having described generally the various parts constituting the system of train control embodying the invention, the operation will be described for different cases, in which certain conditions such as may occur in practice are assumed to exist along the trackway.

Referring to Figs. 1 and 2, for the first condition assume the train under consideration is in the block section A, as shown in Fig. 1, and is about to enter the control section B; that the train has found the road unobstructed and is running without being under the dominance of the train control device K; and that there is no train in the block section C or in the block section E. Since there is no train in the block section C, the track relay 7 is energized from the track battery 4 and the armatures 8, 9, and 10 of said relay are in their upper positions, as shown in Fig. 1. Likewise, the armatures 8¹, 9¹ and 10¹ of the track relay 7¹ of the block section E are in their upper position, since it is assumed that there is no train in the block section E. Under these conditions a difference of potential exists between the ramp 11 and the track rail 1, due to a partial circuit traced as follows: track rail 1, conductor 48, local battery 15, conductors 43, 44 and 45, armature 9 of the track relay 7 in its upper position, conductors 46 and 47 to the ramp 11. As the first pair of wheels 16 130

enter the control section B a pickup circuit for the ramp relay 12 is established as follows: local battery 15, conductors 43 and 49, ramp relay 12, conductors 50 and 51, 5 armature 10¹ of the track relay 7¹ in its upper position, conductor 52, armature 8 of the track relay 7 in its upper position, conductor 53 to the track rail 2 through the wheels 16 and the axle 17 to the track rail 1 10 and along conductor 48 back to the battery 15. It can be seen that the energization of the ramp relay 12 is not possible according to this last mentioned circuit unless the track relays 7 and 7¹ are energized, that is, 15 unless the block sections C and E are unoccupied. When the ramp relay 12 is energized its armature 13 is raised to close a stick circuit through said relay traced as follows: from the local battery 15, conductors 20 43 and 49, ramp relay 12, conductors 50 and 54, armature 13 of the ramp relay 12 in its upper position, conductor 55, rail 2 through the wheels 16 and axle 17 to the rail 1 and then along conductor 48 back 25 to the battery 15. Consequently, once the ramp relay 12 is energized and its armature 13 raised said relay will continue to be energized so long as a pair of wheels remains on the control section B. Also, when 30 the ramp relay 12 is energized its armature 14 is raised to establish a shunt around the armature 9 of the track relay 7, so that the circuit hereinbefore described, which produces a difference of potential between the 35 ramp 11 and the track rail 1, will not be interrupted when the track relay 7 is deenergized and its armature 9 dropped. This shunt is established because, as the vehicle proceeds, the first pair of wheels 16 and the 40 axle 17 will pass into the block section C and deenergize the track relay 7, as will be understood by those skilled in the art, thus causing the armature 9 of said track relay to drop; but since the armature 14 of the 45 ramp relay 12 has been raised a difference of potential is maintained between the ramp 11 and the track rail 1 by reason of said shunt according to the following partial circuit: from the track rail 1, conductor 48, 50 battery 15, conductors 43, 44 and 56, armature 14 of the ramp relay 12 in its upper position and conductors 57 and 47 to the ramp 11. As soon as the last pair of wheels 18 and the axle 19 of the vehicle leave the 55 control section B, the armatures 13 and 14 of the ramp relay will drop and open the circuit which maintains a difference of potential between the ramp 11 and the track rail 1 and also interrupt the stick circuit 60 for said ramp relay.

From the foregoing it can be seen that a difference of potential is maintained between the ramp 11 and the track rail 1, provided there is no train in the block sections C or 65 E, until the last pair of wheels and axle of

the train pass from the short control section B, and, consequently, the condition of the ramp 11 is the same when each shoe 22 carried by the different motor cars or locomotives in the train engage said ramp. 70

As the shoe or plunger 22 strikes the ramp 11 it is raised and the electrical connection between the contact spring 25 and the contact member 26 is broken, thereby interrupting the following normally closed circuit 75 through the control relay 27: local battery 30, conductors 31 and 32, relay 27, conductors 33 and 34, armature 28 in its upper position, conductor 35, contact spring 25, contact member 26 and conductor 36 to the 80 battery 30. Also, as soon as the shoe 22 makes electrical contact with the ramp 11 and shortly before said shoe has been raised far enough to separate the contact spring 25 from the contact member 26, current will be 85 supplied to the control relay 27 from the ramp 11 according to the following circuit: battery 15, conductors 43, 44 and 56, armature 14 of the ramp relay 12 in its upper position, conductors 57 and 47 to the ramp 90 11, shoe 22, conductors 41 and 32, control relay 27, conductors 33 and 42 to the frame 20 through the axles and wheels of the vehicle to the track rail 1 and along conductor 48 back to the battery 15. Consequently, 95 each time the shoe 22 engages a ramp, if there exists a difference of potential between that ramp and the track rail, the control relay 27 will be kept energized and the vehicle may proceed safely. 100

For the next condition, assume that the vehicle is in the block section A and has had an unobstructed way over which to travel; that there is no train in the block C; but that there is a train in the block section E. 105 In this case, a track relay 7¹ of the block section E will be deenergized and its armature 10¹ will drop and interrupt the pickup circuit for the ramp relay 12 hereinbefore set forth; and, consequently, when the first 110 pair of wheels and axle of the vehicle pass on to the short control section B the ramp relay 12 will not be energized as hereinbefore described. However, until the first wheels of the train enter the block section C, 115 a difference of potential is maintained between the ramp 11 and the track rail 1 according to the circuit hereinbefore set forth, since the armature 9 of the track relay 7 is in its upper position. Then, as the train 120 progresses and its first pair of wheels and axle pass in the block section C, the track relay 7 is deenergized and its armature 9 drops, thereby interrupting the circuit which normally maintains a difference of potential 125 between the ramp 11 and the track rail 1. In this way, there is a difference of potential between the ramp 11 and the track rail 1 while the first pair of wheels and axle are on the short control section B, but when this 130

first pair of wheels and axle pass into the block section C this difference of potential ceases. The shoe 22 as it engages the ramp 11 is raised to interrupt the normally closed circuit through the control relay 27, as hereinbefore described, and, during the movement of the train through the control section B, this control relay 27 remains energized; but, as soon as the train enters the block section C, the control relay 27 is deenergized. When the control relay 27 is deenergized its armature 28 drops and interrupts the normally closed circuit through the device K, which controls the operation of the apparatus arranged to control the movement of the vehicle, this normally closed circuit being as follows: battery 37, conductor 38, armature 29 of the control relay 27 in its raised position, conductor 39 through the device C and conductor 40 back to the battery 37. The device K may be constructed to shut off the power and to apply the brakes automatically or may be used to set any suitable train control apparatus of any other description into operation.

Assuming that the block section E is occupied, and that the block section C is not occupied, the ramp 11 may be short enough compared with the length of the control section B and may be located with reference to the insulating joint 3 at the entrance to the block section C so that when the first wheels 16 of the train enter the block section C the first shoe 22 of the train will not yet have reached the ramp 11. In this case, if there is a train in the block section E, no difference of potential will exist between the ramp 11 and the track rail 2 at any time while the train is passing said ramp, since the presence of a train in the block E prevents the ramp relay 12 from being energized and since the first pair of wheels and axle of the train enter the block C and deenergize the track relay 7 before the first shoe 22 of the train makes electrical contact with the ramp 11. With some types of train control apparatus, however, it may be desirable to energize the control relay 27 when a ramp is passed in every case, whether or not there is a train in the block section E, provided the block section C is unoccupied; and then deenergize the control relay 27 if the block section E is occupied. This requirement may be satisfied if the ramp 11 is of such length and so located with reference to the insulating joints 3 that the first shoe 22 of the train will make electrical contact with said ramp before the first pair of wheels and axle of the train enter into the block section C, because, whether the block section E is occupied or not, a difference of potential is maintained between the ramp 11 and the track rail 2 before the first pair of wheels and axle of the train enter into the block C according to the partial circuit controlled

by the armature 9 of the track relay 7, which partial circuit may be traced as follows: track rail 1, conductor 48, battery 15, conductors 43, 44 and 45, armature 9 of the track relay 7 in its upper position, conductors 46 and 47, to the ramp 11.

Another factor which determines the length and position of the ramps 11 may be noted at this time, that is, the front end of a ramp must be a greater distance from the insulating joint 3 at the entrance to the block section C than the distance between the last pair of wheels 18 and axle 19 and the contact shoe 22, in order that the shoe 22 will have left electrical contact with the ramp 11 before the last pair of wheels 18 and axle 19 have left the control section B.

For the next condition to be considered, assume that the train under consideration is in the block section A and about to enter the control section B, and that there is a train in the block section C. In this case the train, before it entered the block section A would have been placed under the dominance of the train control apparatus, since the presence of the train in the block section C would have set the train control apparatus into operation at the entrance to the block section A, in the same way as the presence of a train in the block section E causes the train control apparatus to be set into operation when the train entered the block C, as hereinbefore explained. The presence of the train in the block section C requires that the following train should not enter this block section C, unless with great caution and at a low speed; and, consequently, no difference of potential should exist between the ramp 11 and the track rail 1 so that said following train will not be released from the dominance of its train control apparatus by passing the ramp 11. This absence of any difference of potential between the ramp 11 and the track rail 1 is effected by reason of the fact that the presence of a train in the block section C causes the armature 9 of the track relay 7 to drop and to interrupt the connection between the ramp 11 and the battery 15.

The modified arrangement of circuits shown in Fig. 3 is the same as the arrangement of circuits shown in Figs. 1 and 2, except that a third armature 75 controlled by the ramp relay 12 is inserted in the conductor designated 52 in Figs. 1 and 2, so that said armature 75 is included in the pickup circuit of said ramp relay, said pickup circuit for the modified arrangement shown in Fig. 3 being as follows: battery 15, conductors 43 and 49, ramp relay 12, conductors 50 and 51, armature 10¹ of the ramp relay 7¹ in its upper position, conductor 52, armature 75¹ of the ramp relay 12¹ in its upper position, conductor 52¹, armature 8 of the track relay 7 in its upper

position, conductor 53, track rail 2, wheels 18 and axle 19, track rail 1 and conductor 48 back to the battery 15. The armature 75¹ interrupts this pickup circuit for the 5 ramp relay 12 if a pair of wheels and axle of a train occupy the control section D, since a pair of wheels on said control section causes the ramp relay 12¹ to be energized and its armature 75¹ to be raised. In 10 this way, the presence of a train on the control section D, as well as on either the block section C or E, will prevent the energization of the ramp relay 12.

Since the presence of the train on the 15 control section D prevents the energization of the ramp relay 12, no difference of potential will exist between the ramp 11 and the track rails after the first pair of wheels and axle enter the block section C and the 20 train control device K will be set into operation. Also, the pickup circuit for the ramp relay 12 is interrupted if the relay 12¹ is energized for any reason, as for instance by stray current; or if the armatures of the 25 relay 12¹ do not drop after a train has passed the control section D, the device K on the following train will be set into operation when said following train enters the 30 block section C. From the foregoing it can be seen that the third armature 75 added to the ramp relay 12 provides additional safeguards against improper operation of the system.

In the specific embodiment of the invention shown and described, contact rails or ramps are used; but it is to be understood that the combination of circuits and controlling means constituting my invention is not limited in its application to ramps and 40 may be used in connection with other suitable devices or appliances, the function of which is to transmit some form of a controlling impulse to a passing vehicle or train, these equivalent devices or appliances 45 falling within the scope of my invention being conveniently referred to as impulse devices, impulse transmitting means, and the like.

Although I have particularly described 50 the construction of one physical embodiment of my invention, and explained the operation and principle thereof; nevertheless, I desire to have it understood that the form selected is merely illustrative, but does not 55 exhaust the possible physical embodiments of the idea of means underlying my invention.

What I claim as new and desire to secure by Letters Patent of the United States, is: 60

1. In an automatic train control system, in combination: a trackway adapted for moving vehicles and comprising electrically isolated block sections, a comparatively short control section at the entrance to each of said block sections and electrically isolated

therefrom; an insulated ramp positioned near the entrance to each of said block sections; a relay associated with each ramp for completing a circuit which establishes a difference of potential between said ramp and the track rails; an operating circuit for said relay terminating at the rails of the corresponding short control section; a stick-up circuit for said relay also terminating at the rails of said control section and controlled 70 by the relay itself; and means responsive to the presence of a vehicle on either of the two block sections in advance for breaking said relay operating circuit.

2. In an automatic train control system, 80 in combination: a trackway adapted for moving vehicles and comprising electrically isolated block sections, a comparatively short control section at the entrance to each of said block sections and electrically isolated 85 therefrom; an insulated ramp positioned near the entrance to each of said block sections; a relay associated with each ramp for completing a circuit which establishes a difference of potential between said ramp 90 and the track rails; an operating circuit for said relay terminating at the rails of the corresponding short control section; a stick-up circuit for said relay also terminating at the rails of said control section and controlled 95 by the relay itself; and means responsive to the presence of a vehicle on either of the two block sections in advance or the next short control section in advance for breaking said relay operating circuit. 100

3. In an automatic train control system, in combination: a trackway adapted for moving vehicles and comprising electrically isolated block sections, a comparatively short control section at the entrance to each of 105 said block sections and electrically isolated therefrom; an insulated ramp positioned near the entrance to each of said block sections; a source of current and a relay constituting a track circuit for each of said 110 block sections; a circuit controller operated by each relay and having pairs of cooperating contacts which are closed when said relay is energized; a circuit associated with each block section including one pair of contacts of the circuit controller of the track relay of that block section for maintaining a difference of potential between said ramp at the entrance of that block section and the track rails; a circuit associated with each 120 track relay for shunting said last-mentioned pair of contacts thereof, and means responsive to the presence of a vehicle on the corresponding short control section for closing its corresponding shunting circuit when 125 neither of the next two block sections in advance is occupied.

4. In an automatic train control system, in combination: a trackway adapted for moving vehicles and comprising electrically 130

isolated block sections, a comparatively short control section at the entrance to each of said block sections and electrically isolated therefrom; an insulated ramp positioned near the entrance to each of said block sections; a source of current and a relay constituting a track circuit for each of said block sections; each of said track relays having front contacts which are closed when 5 said relay is energized; a circuit associated with each block section including a front contact of the corresponding track relay for maintaining a difference of potential between said ramp at the entrance of that 10 block section and the track rails; a circuit for shunting said last mentioned front contact of said track relay; a ramp relay having cooperating contacts which are included in the shunting circuit of the corresponding 15 block and which are closed when said ramp relay is energized; and an operating circuit for each ramp relay terminating at the rails of the corresponding short control section and including other front contacts of the 20 track relays of the next two block sections in advance.

5. In an automatic train control system, in combination: a trackway adapted for moving vehicles and comprising electrically isolated block sections, a comparatively short control section at the entrance to each of said block sections and electrically isolated therefrom; an insulated ramp positioned near the entrance to each of said block sections; a source of current and a track relay constituting a track circuit for each of said block sections; each track relay having front 30 contacts which are closed when said relay is energized; a circuit associated with each of said block sections which includes a front contact of the corresponding track relay for maintaining a difference of potential between the corresponding ramp and the track rails; a circuit for shunting the last-mentioned front contact of said track relay; a ramp relay having cooperating contacts included in the shunting circuit of the corresponding block, which are closed when said ramp relay is energized; each ramp relay 35 having a back contact which is opened when said relay is energized; and an operating circuit for each ramp relay terminating at the rails of the corresponding short control section and including the contacts of the track 40 relays of the next two block sections in advance and said back contact of the ramp relay of the next control section in advance.

6. In an automatic train control system, in combination: a trackway adapted for moving vehicles and comprising electrically isolated block sections, a comparatively short control section at the entrance to each of said block sections and electrically isolated therefrom; an insulated ramp positioned near the 45 entrance to each of said block sections; two circuits

for establishing a difference of potential between said ramp and the track rails, one of said circuits being controlled by the presence of a train on the corresponding short control section, and the other being controlled by the presence of a train on the corresponding block section, and means responsive to the presence of a train on either the corresponding block section or the next block section in advance for preventing said 70 first-mentioned circuit from being established.

7. In an automatic train control system, in combination: a trackway adapted for moving vehicles and comprising electrically isolated block sections, a comparatively short control section at the entrance to each of said block sections and electrically isolated therefrom; an insulated ramp positioned near the entrance to each of said block sections; two circuits for establishing a difference of potential between said ramp and the track rails, one of said circuits being controlled by the presence of a train on the corresponding short control section, and the other being 75 controlled by the presence of a train on the corresponding block section, and means responsive to the presence of a train on either the corresponding block section or the next block section in advance for preventing said first-mentioned circuit from being established.

8. In an automatic train control system, in combination: a track for moving vehicles divided into blocks each having a track relay; a comparatively short electrically isolated control section at the entrance to each block; an impulse device associated with each block; a normally closed controlling circuit for each impulse device governed by the track relay of the corresponding block and interrupted when that block is occupied; and normally ineffective means for each block controlled by the track relay thereof and having its operation determined by the presence of a train on the adjacent control section for establishing said controlling circuit independently of the control of said circuit by the track relay of the corresponding block.

9. In an automatic train control system, in combination: a train and a track therefor divided into blocks; a comparatively short electrically isolated control section at the entrance to each block; an impulse device associated with each block; a normally open controlling circuit for each impulse device; means for closing said circuit so long as the corresponding control section is occupied provided the corresponding block and the next block in advance are not occupied; and means on the several vehicles of a train for cooperating with said impulse devices.

10. In an automatic train control system,

in combination: a track divided into blocks provided with track circuits; a comparatively short electrically isolated control section at the entrance to each block; an impulse device associated with each block; a circuit for controlling each impulse device; and means for controlling said circuit, said means being initially rendered effective when the corresponding control section is occupied 5 and the corresponding block and the block next in advance are not occupied, said means after being initially rendered effective being maintained effective so long as the corresponding control section is occupied 10 by a portion of a train.

11. In an automatic train control system for railroads, in combination: a train and a track therefor divided into blocks each having a normally closed track circuit; a comparatively short control section at the entrance to each block; an impulse device associated with each block and arranged to transmit impulses to the vehicles of a passing train both prior to and subsequent to the entrance of the train into such block, the safety controlling condition of each impulse device being normally dependent upon the track circuit of the corresponding block; and means having its initial operation dependent upon the presence of a train on the track circuits of the corresponding block and the next block in advance for causing the safety controlling condition of each impulse device to exist after the entrance of 25 the train into the corresponding control section and so long as such train occupies said control section.

12. In an automatic train control system for railroads, in combination: a train and a track therefor divided into blocks each having a normally closed track circuit; a comparatively short control section at the entrance to each block; a contact ramp associated with each block and arranged to be 40 engaged by the shoes on the vehicles of a passing train both prior to and subsequent to the entrance of a train into said block, said ramp being in its safety controlling condition when energized; a circuit controlled by the track circuit of the corresponding block for normally energizing each ramp; and normally inactive means associated with each ramp and having its initial operation dependent upon the presence of 45 a train on the track circuits of the corresponding block and the next block in advance for causing energization of that ramp upon the entrance of a train into the corresponding control section and for continuing 50 such energization until such train has passed off of the rails of said control section.

13. In an automatic train control system for railroads, in combination: a train and a track therefor divided into blocks each 55 having a normally closed track circuit; a

comparatively short control section at the entrance to each block; an impulse device associated with each block and arranged to transmit impulses to the vehicles of a passing train both prior to and subsequent to 70 the entrance of the train into said block; a controlling circuit associated with each impulse device for placing that device in its safety controlling condition, said controlling circuit being governed by the front contact of the track relay of the corresponding block; a normally open shunt for said front contact of each track relay; means associated with each impulse device and having its initial operation dependent upon the 75 presence of a train on the track circuits of the corresponding block and the next block in advance for closing said shunt circuit upon the entrance of a train into the corresponding controlling section and for maintaining it closed until such train has passed out of said control section.

14. In an automatic train control system for railroads, in combination: a train and a track therefor divided into blocks each having a normally closed track circuit; a comparatively short control section at the entrance to each block; an impulse device associated with each block and arranged to cooperate with elements on the vehicles of a passing train both prior to and subsequent to the entrance of a train into said block, each impulse device being in its safety controlling condition when supplied with current; a circuit controller governed by the 90 track circuit of each block and closed when that block is not occupied; a circuit for normally supplying current to each impulse device including the circuit controller of the track circuit of the corresponding block; a 95 normally open shunt for each circuit controller; a stick relay for closing said shunt when energized; an energizing circuit for each stick relay having its continuity dependent upon the track circuits of the corresponding block and the next block in advance being unshunted and adapted to be established by the presence of a pair of wheels on the corresponding control section; and means for maintaining each stick relay 100 energized after it has been initially energized so long as the corresponding control section is occupied by a pair of wheels.

15. In an automatic train control system for railroads, in combination: a train and a track therefor divided into blocks each having a normally closed track circuit; a comparatively short control section at the entrance to each block; an impulse device associated with each block and arranged to cooperate with elements on the vehicles of a passing train both prior to and subsequent to the entrance of the train into the corresponding block, each impulse device being adapted to assume its safety controlling condition 115

dition when supplied with current; means controlled by the track circuit of the corresponding block for normally supplying current to each impulse device; and means initially controlled by the track circuits of the corresponding block and the next block in advance and adapted to be rendered active by the entrance of a pair of wheels into the corresponding control section for independently supplying current to each impulse device, said last mentioned means after its initial operation has been determined, being maintained in its operated condition so long as a pair of wheels is on the corresponding control section.

16. In an automatic train control system for railroads, in combination: a train and a track therefor divided into blocks each having a normally closed track circuit; an insulated rail section at the entrance to each block; an impulse device associated with each block and adapted to assume a safety controlling condition when supplied with current; a normally open controlling circuit for each impulse device including a source of current and adapted when closed to cause the corresponding impulse device to assume its safety controlling condition; and normally inactive means having its initial operation dependent upon the presence of a train on the track circuits of the corresponding block and the next block in advance for closing said controlling circuit when a pair of wheels occupied the corresponding insulated rail section and for maintaining it closed so long as said rail section is occupied.

17. In an automatic train control system for railroads, in combination: a track divided into blocks each having a normally closed track circuit; a comparatively short control section at the entrance to each block; an impulse device associated with each block and normally in its safety controlling condition when the corresponding block is unoccupied; a relay associated with each impulse device and adapted when energized to cause that impulse device to assume its safety controlling condition independently of the subsequent shunting of the track circuit of the corresponding block; and an energizing circuit for each of said relays responsive to the presence of a pair of wheels on the corresponding control section and controlled by the track circuits of the corresponding block and the block next in advance.

18. In an automatic train control system for railroads divided into blocks each having a normally closed track circuit and a comparatively short insulated rail section at the entrance thereto, the combination with an impulse device associated with each block and adapted to transmit controlling impulses to passing vehicles; of automatic train con-

trolling means on the passing vehicles including a relay influenced by the controlling condition of said impulse devices along the track, said relay being either re-energized or maintained energized by an impulse device in the safety controlling condition, and being de-energized or maintained de-energized by an impulse device in the danger controlling condition; and means for causing the controlling condition of each impulse device to be dependent in succession upon the track circuit of the corresponding block, and then upon the track circuit of both the corresponding block and the next block in advance, said means also acting to maintain said impulse device in the same existing controlling condition after a passing train enters the corresponding block and so long as any part of such train remains on the corresponding insulated rail section.

19. In an automatic train control system for railroads having blocks provided with normally closed track circuits, the combination with an impulse device associated with each block; of automatic train control means on the passing vehicles including a relay influenced by the controlling condition of said impulse devices, said relay being either re-energized or maintained energized by an impulse device in the safety controlling condition and being de-energized or maintained de-energized by an impulse device in the danger controlling condition; and means for causing the controlling condition of each impulse device to be dependent in succession upon the track circuit of the corresponding block, and then upon the track circuits of both the corresponding block and the next block in advance.

20. In an automatic train control system for railroads having blocks provided with normally closed circuits, the combination with an impulse device at the entrance to each block; of automatic train control means on the passing vehicles including a control device adapted to be influenced by the controlling condition of said impulse devices, said control device being rendered inactive or maintained inactive by the safety controlling condition of an impulse device, and being rendered active or maintained active by its danger controlling condition; and means responsive to the presence of a pair of wheels of a train adjacent to an impulse device and controlled by the track circuits of both the corresponding block and the next block in advance for placing that impulse device in the safety controlling condition when said blocks are not occupied, said means also acting to maintain such safety controlling condition until all pairs of wheels of the train have passed that impulse device, regardless of the entrance of such train into the corresponding block.

WINTHROP K. HOWE.
